(57) **CLAIM**

We claim the ornamental design for an injection device, as shown and described.

DESCRIPTION

FIG. 1 is a perspective view of the back, right and top of the injection device;

FIG. 2 is a perspective view of the front, right and side thereof;

FIG. 3 is a top plan view thereof;

FIG. 4 is a bottom plan view thereof;

FIG. 5 is a right side elevation view thereof;

FIG. 6 is a left side elevation thereof;

FIG. 7 is a front elevation view thereof;

FIG. 8 is a back elevation view thereof;

FIG. 9 is a perspective view of the back, right and top of the injection device with the protective cap removed from the proximal end;

FIG. 10 is a perspective view of the front, right, and side thereof;

FIG. 11 is a right side elevation view thereof;

FIG. 12 is a top plan view thereof; and,

FIG. 13 is a front elevation view thereof.

The broken lines in the drawings illustrate portions of the injection device that form no part of the claimed design.

1 Claim, 9 Drawing Sheets
